US010272317B2

(12) **United States Patent**
Watterson

(10) **Patent No.:** US 10,272,317 B2
(45) **Date of Patent:** Apr. 30, 2019

(54) **LIGHTED PACE FEATURE IN A TREADMILL**

(71) Applicant: **ICON Health & Fitness, Inc.**, Logan, UT (US)

(72) Inventor: **Scott R. Watterson**, Providence, UT (US)

(73) Assignee: **ICON Health & Fitness, Inc.**, Logan, UT (US)

(*) Notice: Subject to any disclaimer, the term of this patent is extended or adjusted under 35 U.S.C. 154(b) by 32 days.

(21) Appl. No.: **15/460,074**

(22) Filed: **Mar. 15, 2017**

(65) **Prior Publication Data**

US 2017/0266534 A1 Sep. 21, 2017

Related U.S. Application Data

(60) Provisional application No. 62/310,300, filed on Mar. 18, 2016.

FIG. 2

FIG. 3

FIG. 4

FIG. 5

FIG. 6

LIGHTED PACE FEATURE IN A TREADMILL

RELATED APPLICATIONS

This application claims priority to U.S. patent application Ser. No. 62/310,300 titled "Lighted Pace Feature in a Treadmill" and filed on 18 Mar. 2016, which application is herein incorporated by reference for all that it discloses.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user will use an aerobic exercise machine to have an aerobic workout indoors. One type of aerobic exercise machine is a treadmill, which is a machine that has a running deck attached to a support frame. The running deck can support the weight of a person using the machine. The running deck incorporates a conveyor belt that is driven by a motor. A user can run or walk in place on the conveyor belt by running or walking at the conveyor belt's speed. The speed and other operations of the treadmill are generally controlled through a control module that is also attached to the support frame and within a convenient reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical trainers, rowing machines, stepper machines, and stationary bikes to name a few.

One type of treadmill is disclosed in U.S. Patent Publication No. 2009/0176629 issued to Hwa Cho Yi. In this reference, an automatic speed-controlled treadmill uses a pressure sensor array. The automatic speed-controlled treadmill includes a walking belt, a pressure sensor array including pressure sensors for detecting loads of the exerciser's feet and outputting the detected loads of the feet as load detection signals, a pace speed status storage unit for storing a pace speed and variation in pace speed of the exerciser, and a control unit provided with an algorithm for calculating a pace speed of the exerciser using the load detection signals, calculating a difference between a previous pace speed and a current pace speed as the variation in pace speed, calculating the exercise center of the exerciser, and proportionally accelerating/decelerating a driving speed of the walking belt in consideration of the variation in pace speed and the exercise center.

SUMMARY

In one embodiment, a treadmill includes an exercise deck. The exercise deck includes a platform, a first pulley attached to the platform in a front portion, a second pulley attached

to the platform in a second portion, a tread belt surrounding the first and second pulley, and a pacing mechanism incorporated into the platform.

The pacing mechanism may include multiple lights distributed along a length of the platform that illuminate sequentially based at least in part on a speed of the tread belt.

The pacing mechanism may include a light.

The light may be set to temporarily illuminate during predetermined duration of time at a frequency based on at least in part on a speed of the tread belt.

The pace may be based on at least in part on a speed of the treadmill.

The treadmill may include a console, memory, and a processor. The memory may include programmed instructions, when executed, that cause the processor to selectively illuminate one of multiple lights based on a pace.

The programmed instructions, when executed, may cause the processor to receive a pace input from a user.

The programmed instructions, when executed, may cause the processor to execute a programmed exercise routine where the exercise routine contains the pace.

The pacing mechanism may include a first portion on a first side of the platform between the front portion and the rear portion and a second portion on a second side of the platform between the front portion and the portion.

The first portion may include a first subset of multiple lights distributed along a length of the platform that illuminate sequentially based on a pace and a second subset of the multiple lights distributed along the length of the platform that illuminate sequentially based on the pace.

The first subset of the multiple lights may illuminate sequentially based on at least in part on a speed and a movement that a user's first foot has to travel to maintain the pace and wherein the second subset of the multiple lights illuminate sequentially based on at least in part on the speed and the movement that a user's second foot has to travel to maintain the pace.

In one embodiment, a treadmill includes an exercise deck. The exercise deck includes a platform, a first pulley attached to the platform in a front portion, a second pulley attached to the platform in a second portion, a tread belt surrounding the first and second pulley, and multiple lights distributed along a length of the platform.

The multiple lights may illuminate sequentially based on at least in part on a speed of the tread belt.

The treadmill may include a console, memory, and a processor. The memory may include programmed instructions, when executed, that cause the processor to selectively illuminate one of multiple lights based on a pace.

The programmed instructions, when executed, may cause the processor to receive a pace input from a user.

The programmed instructions, when executed, may cause the processor to execute a programmed exercise routine where the exercise routine contains the pace.

The pacing mechanism may include a first portion on a first side of the platform between the front portion and the rear portion and a second portion on a second side of the platform between the front portion and the portion.

The first portion may include a first subset of multiple lights distributed along a length of the platform that illuminate sequentially based on a pace and a second subset of the multiple lights distributed along the length of the platform that illuminate sequentially based on the pace.

The first subset of the multiple lights may illuminate sequentially based on at least in part on a speed and a movement that a user's first foot has to travel to maintain the pace and wherein the second subset of the multiple lights

illuminate sequentially based on at least in part on the speed and the movement that a user's second foot has to travel to maintain the pace.

In one embodiment, a treadmill includes an exercise deck. The exercise deck includes a platform, a first pulley attached to the platform in a front portion, a second pulley attached to the platform in a second portion, a tread belt surrounding the first and second pulley, a pacing mechanism incorporated into the platform, the pacing mechanism includes multiple lights distributed along a length of the platform that illuminate sequentially based at least in part on a speed of the tread belt, a first portion on a first side of the platform between the front portion and the rear portion where a first subset of multiple lights are distributed along a length of the platform that illuminate sequentially based at least in part on the speed of the tread belt, and a second portion on a second side of the platform between the front portion and the portion where a second subset of the multiple lights distributed along the length of the platform that illuminate sequentially based at least in part on the speed of the tread belt.

BRIEF DESCRIPTION OF THE DRAWINGS

The accompanying drawings illustrate various embodiments of the present apparatus and are a part of the specification. The illustrated embodiments are merely examples of the present apparatus and do not limit the scope thereof.

FIG. 1 illustrates a perspective view of an example of a treadmill in accordance with the present disclosure.

FIG. 2 illustrates a perspective view of an example of a treadmill in accordance with the present disclosure.

FIG. 3 illustrates a top view of an example of a treadmill in accordance with the present disclosure.

FIG. 4 illustrates a top view of an example of a treadmill in accordance with the present disclosure.

FIG. 5 illustrates a block diagram of an example of a pacing mechanism in accordance with the present disclosure.

FIG. 6 illustrates a perspective view of an example of a treadmill in accordance with the present disclosure.

Throughout the drawings, identical reference numbers designate similar, but not necessarily identical, elements.

DETAILED DESCRIPTION

For purposes of this disclosure, the term "aligned" means parallel, substantially parallel, or forming an angle of less than 35.0 degrees. For purposes of this disclosure, the term "transverse" means perpendicular, substantially perpendicular, or forming an angle between 55.0 and 125.0 degrees. Also, for purposes of this disclosure, the term "length" means the longest dimension of an object. Also, for purposes of this disclosure, the term "width" means the dimension of an object from side to side. For the purposes of this disclosure, the term "above" generally means superjacent, substantially superjacent, or higher than another object although not directly overlying the object. Further, for purposes of this disclosure, the term "mechanical communication" generally refers to components being in direct physical contact with each other or being in indirect physical contact with each other where movement of one component affect the position of the other.

FIG. 1 depicts an example of a treadmill 100 having a deck 102 with a first pulley disposed in a first portion of the deck 102 and a second pulley incorporated into a second portion of the deck 102. A tread belt 104 surrounds the first pulley and the second pulley. A motor 106 is in mechanical

communication with either the first pulley or the second pulley. A cover 108 is superjacent the motor 106.

The treadmill 100 also includes a pacing mechanism which includes a light 110 incorporated into the side of the deck.

FIG. 2 depicts an example of a treadmill 200 that includes a deck 202 and an upright structure 204. The upright structure 204 includes a console 206 and incorporates at least one input mechanism 208 and a display 210. The input mechanism 208 can control at least one parameter of the treadmill, such as the speed of the tread belt, the incline of the deck 202, a climate control, entertainment, and so forth.

The deck includes a platform 212 with a front pulley and a rear pulley. A tread belt 214 surrounds the front and rear pulleys. The platform 212 includes portions of the deck 202 that are adjacent to the tread belt's edges. In the example of FIG. 2, these regions adjacent to the tread belt include multiple lights 216 distributed along a length of the deck 202.

FIG. 3 depicts a top view of a deck 300. In this example, the deck 300 includes a tread belt 302 and lights 304 positioned along the sides 306, 308 of the tread belt 302.

FIG. 4 depicts a top view of the deck 400 and the lights 402. In this example, a first subset 404 of the lights 402 is positioned on a first side 406 of the deck 400, and a second subset 408 of the lights 402 is positioned on a second side 410 of the deck 400. A user's first foot is represented with a first foot print 412, and a user's second foot is represented with a second foot print 414.

The lights 402 illuminate to set a pace for the user based on the speed of the tread belt 416. In some cases, the user's stride is determined or inputted into the treadmill, and the pace is also determined based, in part, on the user's stride. Based on the pace, a pacing mechanism of the treadmill 35 determines how fast the user's feet have to move to keep up with the tread belt's movements. The first subset 404 of lights 402 illuminate in a sequential order at the pace that the user's first foot has to move to keep up with the pace. Likewise, the second subset 408 of lights 402 illuminate in a sequential order at the pace that the user's second foot has to move to keep up with the pace. The illumination timing of the first subset 404 is matched with the first foot, and the illumination timing of the second subset 408 is matched with the second foot. Thus, the illumination timing of the first

subset 404 and the second subset 408 of lights 402 is offset since the placement of the first and second feet on the tread belt are offset from each other. The illumination of each light is temporary for a predetermined amount of time. The frequency of the light's illumination is based on the pace. In those circumstances where the user is running at the pace set with the pacing mechanism, the user's first foot appears to move in unison with the illumination of the first subset 404 of lights 402, and the user's second foot appears to move in unison with the illumination of the second subset 408 of lights 402.

FIG. 5 depicts an example of a pacing mechanism 500. In this example, the pacing mechanism 500 includes processing resources 502 and memory resources 504. The memory resources 504 may cause the processing resources 502 to carry out functions programmed in the memory resources 504. In this example, the memory resources 504 include a belt speed determiner 506, a pace input determiner 508, a programmed routine executor 510, and a pace determiner 512.

The processing resources 502 may be in communication with I/O resources, which may include a receiver, a transmitter, a transceiver, another type of communication device, 65

or combinations thereof. Further, the processing resources 402 may be in direct communication or in communication through the I/O resources with a first light 514, a second light 516, other lights, or combinations thereof.

FIG. 6 depicts an example of the treadmill 600 with a deck 602. In this example, just a single side 604 of the deck 602 includes the lights 606 that illuminate based at least in part on the tread belt's speed.

GENERAL DESCRIPTION

In general, the invention disclosed herein may provide users with a treadmill that can pace a user of a treadmill. A pacing mechanism incorporated into the treadmill can help the user stay on pace by providing indicators that help the user visually understand how fast the user has to move his or her feet to maintain the pace.

The exercise deck may include a platform that has a first pulley located in a front portion of the deck and a second pulley located in a rear portion of the deck. A tread belt may surround the first and second pulleys and provide a surface on which the user may exercise. At least one of the first pulley and the second pulley may be connected to a motor so that when the motor is active, the pulley rotates. As the pulley rotates, the tread belt moves as well. The user may exercise by walking, running, or cycling on the tread belt's moving surface. In other examples, the tread belt is moved with the user's own power.

The exercise deck may be capable of having its front portion raised and lowered as well as its rear portion raised and lowered to control the lengthwise slope of the running deck. With these elevation controls, the orientation of the running deck can be adjusted as desired by the user or as instructed by a programmed workout. In those examples where the treadmill is involved with simulating a route that involves changes in elevation, the running deck can be oriented to mimic the elevation changes in the route.

In some cases, the treadmill includes a console. The console may locate the input mechanism within a convenient reach of the user to control the operating parameters of the exercise deck. For example, the control console may include controls to adjust the speed of the tread belt, adjust a volume of a speaker integrated into the treadmill, adjust an incline angle of the running deck, adjust a decline of the running deck, adjust a lateral tilt of the running deck, select an exercise setting, control a timer, change a view on a display of the control console, monitor the user's heart rate or other physiological parameters during the workout, perform other tasks, or combinations thereof. Buttons, levers, touch screens, voice commands, or other mechanisms may be incorporated into the control console incorporated into the treadmill and can be used to control the capabilities mentioned above. Information relating to these functions may be presented to the user through the display. For example, a calorie count, a timer, a distance, a selected program, an incline angle, a decline angle, a lateral tilt angle, another type of information, or combinations thereof may be presented to the user through the display.

The treadmill may include preprogrammed workouts that simulate an outdoor route. In other examples, the treadmill has the capability of depicting a real world route. For example, the user may input instructions through the control console, a mobile device, another type of device, or combinations thereof to select a course from a map. This map may be a map of real world roads, mountain sides, hiking trails, beaches, golf courses, scenic destinations, other types of locations with real world routes, or combinations thereof.

In response to the user's selection, the display of the control console may visually depict the beginning of the selected route. The user may observe details about the location, such as the route's terrain and scenery. In some examples, the display presents a video or a still frame taken of the selected area that represents how the route looked when the video was taken. In other examples, the video or still frame is modified in the display to account for changes to the route's location, such as real time weather, recent construction, and so forth. Further, the display may also add simulated features to the display, such as simulated vehicular traffic, simulated flora, simulated fauna, simulated spectators, simulated competitors, or other types of simulated features. While the various types of routes have been described as being presented through the display of the control console, the route may be presented through another type of display, such as a home entertainment system, a nearby television, a mobile device, another type of display, or combinations thereof.

In addition to simulating the route through a visual presentation of a display, the treadmill may also modify the orientation of the running deck to match the inclines and slopes of the route. For example, if the beginning of the simulated route is on an uphill slope, the running deck may be caused to alter its orientation to raise the front portion of the running deck. Likewise, if the beginning of the simulated route is on a downward slope, the rear portion of the running deck may be caused to elevate to simulate the decline in the route. Also, if the route has a lateral tilt angle, the running deck may be tilted laterally to the appropriate side of the running deck to mimic the lateral tilt angle.

As the user begins to walk or run on the running deck, the display may change the scenery to mimic what the user would see if the user were actually at the real world location of the selected route. For example, a tree or another object located along the route that appears to be in the distance when the user is simulated to be at the beginning of the route may appear progressively closer as the user walks or runs on the running deck based on the speed at which the user is simulated to be traveling. Additionally, as the inclines and slopes of the simulated route change as the user progresses along the simulated route, the running deck can adjust to account for these terrain changes. For example, if the steepness of an uphill incline increases in the route, the running deck can likewise increase the incline of the running deck to mimic the change in steepness. Further, if the lateral angle of the route changes, the running deck can tilt laterally to one side to mimic the route's lateral angle.

While the programmed workout or the simulated environment may send control signals to orient the deck, the user may, in some instances, override these control signals with inputs from the console. For example, if the programmed workout or the simulated environment cause the deck to be steeper than the user desires, the user can adjust the deck's orientation through the console.

The treadmill may also include a pacing mechanism that creates visible cues for the user to follow to maintain or get onto the appropriate pace. The pacing mechanism may determine the pace for the user based, at least in part, on the speed of the tread belt. Other factors that may be considered by the pacing mechanism include the user's stride, the user's height, the incline of the deck, other factors, or combinations thereof.

The pacing mechanism may obtain the user's stride length from the user. In some cases, the user may input the stride length into the treadmill's console. In other examples, the pacing mechanism may have access to a personal profile of the user. In this circumstance, the personal profile may

include the user's stride length among other types of information. For example, the other types of information may include the user's age, health, fitness history, health history, gender, height, weight, body weight composition, other types of information, or combinations thereof.

In alternative embodiments, the pacing mechanism may determine the user's stride length. For example, the treadmill may include sensors that can measure parameters indicative of the user's stride length. In one case, pressure sensors may be incorporated into the deck that determines where the user's feet land and come off of the tread belt. In other examples, cameras are employed on the treadmill to determine the user's stride length. In other examples, motor loads can be compared to the tread belt's speed to determine how long the user's feet are in contact with the tread belt. In yet other examples, the user's shoe may include a magnet or another type of detectable object that can be tracked with sensors on the treadmill or associated with the treadmill to determine the user's stride length.

The pacing mechanism may include a light that is incorporated into the treadmill's deck. The light may be located in the front portion of the deck, side portions of the deck, rear portions of the deck, the handle bars, the console, the upright structure, other locations on the treadmill, or combinations thereof. In one situation, the light may illuminate at a frequency that corresponds to the time that the user's foot has to land on the tread belt to maintain the pace. In another situation, the light may illuminate at a frequency that corresponds to the time that the user's foot has to come off of the tread belt to maintain the pace. The light can be located on the treadmill so that the light is easily visible to the user during the performance of the user's workout.

In another example, the pace setting device includes multiple lights that are distributed along at least one side of the treadmill's deck. These lights may form a line along the deck's length. Each light in the line may correspond to a location that the user's foot has to be to maintain the pace. Thus, the lights may temporarily illuminate when the user's foot should be within the corresponding location on the tread belt. Accordingly, as the user's foot is to move along the length of the deck, the lights on the deck's side illuminate one by one in a sequential order. In this example, if the user's foot is on pace and timed with the pacing mechanism, the user's foot moves past the lights as the lights are illuminating. As the user's foot reaches the rear portion of the treadmill, the user lifts his or her foot off of the tread belt and returns the foot to the forward portion of the tread belt. Likewise, the lights on the deck's side illuminate in a sequential order from the deck's forward lights progressively towards the deck's rearward lights. At that moment when the user's foot is to be returned to the forward position on the tread belt, one of the deck's forward lights illuminates indicating that the user's foot is to return to maintain the pace. The deck's next rearward light to the forward illuminating light then lights up as the user's foot is now moving down the deck. Then the adjacent light on the rearward side to the most recently illuminated light also lights up after a short delay as the user's foot is to move past the adjacent light towards the rearward portion of the deck. Thus, each light along the deck lights up as the foot moves past each light until the foot reaches the location where the foot is to be lifted off of the tread belt. The corresponding light to the lift-off location is the last light in the line to illuminate before one of the forward lights illuminates.

In some cases, the forward light that illuminates when the foot is returned is the forward most light in the line. But, in some cases, another light in the forward section of the

treadmill lights up. In this circumstance, the user's stride length may not be long enough to where the user can comfortably reach to the location that corresponds with the forward most light. In other circumstances, the pacing mechanism may encourage the user to run at a stride that is less than what the user can comfortably run at.

Similarly, the last rearward light that illuminates when the foot is to be lifted off of the tread belt may be the rearward most light in the line of lights. But, in some cases, another light in the rearward section of the deck may be the last light to light up. In this circumstance, the user's stride length may not be long enough to where the user can comfortably reach the location that corresponds with the rearward most light. In other circumstances, the pacing mechanism may encourage the user to run at a stride that is less than what the user can comfortably run at.

The pacing mechanism may encourage the user to shorten his or her stride when the deck is inclined, declined, tilted, or otherwise oriented in a manner that may benefit from a shorter stride. In other examples, the simulated environment depicted in the user's console may include a snow patch or other type of terrain where a user may benefit from changing his or her stride if the user were in the actual environment being simulated. In this case, as part of the simulation, the pacing mechanism may encourage the user to shorten or otherwise change his or her stride. In yet another example where the user is following a programmed workout, changing the user's stride length may be part of the programmed workout. The programmed workout may incorporate stride length changes to change the intensity of the workout. The variable intensity and continuous nature of changing the user's stride may place stress on both the user's aerobic and anaerobic systems. These types of stress may build the user's strength, increase endurance, promote fat burning, and increase fitness ability for sports that involve changing intensities.

In another embodiment, a first subset of lights may be incorporated along the deck's length on a first side of the deck, and a second subset of lights may be incorporated along the deck's length on a second side of the deck. The first subset of lights may set the pace for the user's first foot proximate the first side, and the second subset of lights may set the pace for the user's second foot proximate the second side. Accordingly, the first subset of lights and the second subset of lights are offset to mimic the running patterns intended for each of the user's feet to maintain the pace.

In some embodiments, when a first light illuminates, a second light, adjacent to the first light, illuminates before the first light turns off. In some instances, the first light may have turned off before the second light is illuminated. Further, the second light may illuminate within one minute of the first light illuminating, within ten seconds of the first light illuminating, with five seconds of the first light illuminating, within one second of the first light illuminating, within 100 microseconds of the first light illuminating, within another time period, or combinations thereof.

Any appropriate number of lights may be positioned along the length of the deck. In one example, a single light is positioned along the length of the deck to pace the user. In another example, two to five lights are used along a single side of the deck to pace the user. In yet another example, six to twenty lights are used along a single side of the deck to pace the user. In an additional example, over twenty lights are used along a single side of the deck to pace the user.

In some cases, the lights used to pace the user are the same color. In yet another example, at least some of the lights are different colors. For example, the lights along the same side

of the deck may have different colors. In another example, a first subset of lights on a first side of the deck may have a different color than a second subset of lights positioned on a second side of the deck.

While the examples above have been described with reference to multiple lights being arranged along the length of the deck in a line, any appropriate type of arrangement may be used in accordance with the principles described in the present disclosure. For example, the lights may be arranged in a curved arrangement, a zigzag arrangement, another type of arrangement, or combinations thereof.

The pacing mechanism may include a combination of hardware and programmed instructions for executing the functions of the pacing mechanism. The pacing mechanism may include processing resources that are in communication with memory resources. Processing resources include at least one processor and other resources used to process the programmed instructions. As described herein, the memory resources may represent generally any memory capable of storing data such as programmed instructions or data structures used by the pacing mechanism.

The processing resources may include I/O resources that are capable of being in communication with a remote device that stores the user information, workout history, external resources, databases, or combinations thereof. The remote device may be a mobile device, a cloud based device, a computing device, another type of device, or combinations thereof. In some examples, the pacing mechanism communicates with the remote device through a mobile device which relays communications between the pacing mechanism and the remote device. In other examples, the mobile device has access to information about the user.

The remote device may execute a program that can provide useful information to the pacing mechanism. An example of a program that may be compatible with the principles described herein includes the iFit program which is available through www.ifit.com. An example of a program that may be compatible with the principles described in this disclosure is described in U.S. Pat. No. 7,980,996 issued to Paul Hickman. U.S. Pat. No. 7,980,996 is herein incorporated by reference for all that it discloses. In some examples, the user information accessible through the remote device includes the user's age, gender, body composition, height, weight, health conditions, other types of information, or combinations thereof.

The processing resources, memory resources, and remote devices may communicate over any appropriate network and/or protocol through the input/output resources. In some examples, the input/output resources includes a transmitter, a receiver, a transceiver, or another communication device for wired and/or wireless communications. For example, these devices may be capable of communicating using the ZigBee protocol, Z-Wave protocol, BlueTooth protocol, Wi-Fi protocol, Global System for Mobile Communications (GSM) standard, another standard, or combinations thereof. In other examples, the user can directly input some information into the pacing mechanism through a digital input/output mechanism, a mechanical input/output mechanism, another type of mechanism, or combinations thereof.

The memory resources may include a computer readable storage medium that contains computer readable program code to cause tasks to be executed by the processing resources. The computer readable storage medium may be a tangible and/or non-transitory storage medium. The computer readable storage medium may be any appropriate storage medium that is not a transmission storage medium. A non-exhaustive list of computer readable storage medium

types includes non-volatile memory, volatile memory, random access memory, write only memory, flash memory, electrically erasable program read only memory, magnetic based memory, other types of memory, or combinations thereof.

The memory resources may include a belt speed determiner that represents programmed instructions that, when executed, causes the processing resources to determine the speed of the belt. The belt speed determiner may measure the speed of the belt with a sensor to determine the belt's speed. The memory resources may also include a pace input receiver that represents programmed instructions that, when executed, causes the processing resources to receive an input about the pace. In this example, the user may input that the tread belt is to move at a certain speed. The pacing mechanism may use the user's input to determine what speed the tread belt is traveling. Also, the memory resources may include a programmed routine executor that represents programmed instructions that, when executed, causes the processing resources to execute a programmed workout and/or a simulated environment. In this case, the programmed workout and/or simulated workout may communicate the belt's speed to the pacing mechanism.

Each of the belt speed determiner, the pace input receiver, and the programmed routine executor may be used to determine the tread belt's speed. The pace determiner may represent programmed instructions that, when executed, cause the processing resources to determine the pace that the user has to move to maintain the pace. In some cases, the memory resources further include a stride length determiner that represents programmed instructions that, when executed, cause the processing resources to determine the user's stride length. In this example, the pace determiner may determine the pace based on the belt speed and on the user's stride. The pacing mechanism may also include a stride adjustor that adjusts the stride depicted with the lights by changing the range of lights that illuminate.

Further, the memory resources may be part of an installation package. In response to installing the installation package, the programmed instructions of the memory resources may be downloaded from the installation package's source, such as a portable medium, a server, a remote network location, another location, or combinations thereof. Portable memory media that are compatible with the principles described herein include DVDs, CDs, flash memory, portable disks, magnetic disks, optical disks, other forms of portable memory, or combinations thereof. In other examples, the program instructions are already installed. Here, the memory resources can include integrated memory such as a hard drive, a solid state hard drive, or the like.

In some examples, the processing resources and the memory resources are located within the treadmill, a mobile device, an external device, another type of device, or combinations thereof. The memory resources may be part of any of these device's main memory, caches, registers, non-volatile memory, or elsewhere in their memory hierarchy. Alternatively, the memory resources may be in communication with the processing resources over a network. Further, data structures, such as libraries or databases containing user and/or workout information, may be accessed from a remote location over a network connection while the programmed instructions are located locally.

What is claimed is:

1. A treadmill, comprising:
an exercise deck, the exercise deck including:
a platform;
a first pulley attached to the platform in a front portion;

11

a second pulley attached to the platform in a rear portion;
 a tread belt surrounding the first pulley and the second pulley; and
 a pacing mechanism incorporated into the platform, wherein the pacing mechanism includes multiple lights that illuminate sequentially.

2. The treadmill of claim 1, wherein the multiple lights are distributed along a length of the platform.

3. The treadmill of claim 1, wherein the pacing mechanism includes a first set of multiple lights and a second set of multiple lights.

4. The treadmill of claim 3, wherein the first set of multiple lights and second set of multiple lights are set to temporarily illuminate during a predetermined duration of time at a frequency based at least in part on a speed of the tread belt.

5. The treadmill of claim 1, wherein a pace of the pacing mechanism is based on at least in part on a speed of the treadmill.

6. The treadmill of claim 1, further including:
 a console; and
 memory and a processor, the memory including programmed instructions, when executed, that cause the processor to selectively illuminate one of multiple lights based on a pace.

7. The treadmill of claim 6, wherein the programmed instructions, when executed, further cause the processor to receive a pace input from a user.

8. The treadmill of claim 6, wherein the programmed instructions, when executed, further cause the processor to execute a programmed exercise routine where the programmed exercise routine contains the pace.

9. The treadmill of claim 1, wherein the pacing mechanism further includes:

a first portion on a first side of the platform between the front portion and the rear portion; and
 a second portion on a second side of the platform between the front portion and the rear portion.

10. The treadmill of claim 9, wherein the first portion includes:

a first subset of multiple lights distributed along a length of the platform that illuminate sequentially based on a pace; and
 a second subset of the multiple lights distributed along the length of the platform that illuminate sequentially based on the pace.

11. The treadmill of claim 10, wherein the first subset of the multiple lights illuminate sequentially based at least in part on a speed and a movement that a user's first foot has to travel to maintain the pace; and wherein the second subset of the multiple lights illuminate sequentially based at least in part on the speed and the movement that a user's second foot has to travel to maintain the pace.

12. A treadmill, comprising:
 an exercise deck, the exercise deck including:
 a platform;
 a first pulley attached to the platform in a front portion;
 a second pulley attached to the platform in a rear portion;
 a tread belt surrounding the first pulley and the second pulley; and
 multiple lights distributed along a length of the platform.

12

13. The treadmill of claim 12, wherein the multiple lights illuminate sequentially based at least in part on a speed of the tread belt.

14. The treadmill of claim 12, further including:
 a console; and
 memory and a processor, the memory including programmed instructions, when executed, that cause the processor to selectively illuminate one of multiple lights based on a pace.

15. The treadmill of claim 14, wherein the programmed instructions, when executed, further cause the processor to receive a pace input from a user.

16. The treadmill of claim 14, wherein the programmed instructions, when executed, further cause the processor to execute a programmed exercise routine where the programmed exercise routine contains the pace.

17. The treadmill of claim 12, wherein the multiple lights further includes:

20 a first portion on a first side of the platform between the front portion and the rear portion; and
 a second portion on a second side of the platform between the front portion and the rear portion.

18. The treadmill of claim 17, wherein the first portion includes:

a first subset of multiple lights distributed along the length of the platform that illuminate sequentially based on a pace; and
 a second subset of the multiple lights distributed along the length of the platform that illuminate sequentially based on the pace.

19. The treadmill of claim 18, wherein the first subset of the multiple lights illuminate sequentially based at least in part on a speed and a movement that a user's first foot has to travel to maintain the pace; and wherein the second subset of the multiple lights illuminate sequentially based at least in part on the speed and the movement that a user's second foot has to travel to maintain the pace.

20. A treadmill, comprising:
 an exercise deck, the exercise deck including:
 a platform;
 a first pulley attached to the platform in a front portion;
 a second pulley attached to the platform in a rear portion;
 a tread belt surrounding the first pulley and the second pulley;
 a pacing mechanism incorporated into the platform; the pacing mechanism includes multiple lights distributed along a length of the platform that illuminate sequentially based at least in part on a speed of the tread belt;
 a first portion on a first side of the platform between the front portion and the rear portion where a first subset of multiple lights are distributed along the length of the platform that illuminate sequentially based at least in part on the speed of the tread belt; and
 a second portion on a second side of the platform between the front portion and the rear portion where a second subset of the multiple lights distributed along the length of the platform that illuminate sequentially based at least in part on the speed of the tread belt.
